(57) **CLAIM**

The ornamental design for a modular organizer set, as shown and described.

DESCRIPTION

FIG. 1 is a perspective view of a modular organizer set showing my new design;

FIG. 2 is a front, top, left perspective view of a first module from the organizer set, shown separately for clarity of the disclosure;

FIG. 3 is a back, bottom, left perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a back, top, left perspective view of the first module with the drawers slid out of its housing;

FIG. 11 is a front, top, left perspective view of the first module with the drawers slid out of its housing;

FIG. 12 is a front, top, left perspective view of a second module from the organizer set, shown separately for clarity of the disclosure;

FIG. 13 is a back, bottom, left perspective view thereof;

FIG. 14 is a front view thereof;

FIG. 15 is a back view thereof;

FIG. 16 is a left side view thereof;

FIG. 17 is a right side view thereof;

FIG. 18 is a top view thereof;

FIG. 19 is a bottom view thereof;

FIG. 20 is a back, top, left perspective view of the second module with the drawers slid out of its housing;

FIG. 21 is a front, top, left perspective view of the second module with the drawers slid out of its housing;

FIG. 22 is a front, top, left perspective view of a third module from the organizer set, shown separately for clarity of the disclosure;

FIG. 23 is a back, bottom, left perspective view thereof;

FIG. 24 is a front view thereof;

FIG. 25 is a back view thereof;

FIG. 26 is a left side view thereof;

FIG. 27 is a right side view thereof;

FIG. 28 is a top view thereof;

FIG. 29 is a bottom view thereof;

FIG. 30 is a back, top, left perspective view of the third module with the drawers slid out of its housing;

(Continued)

FIG. 31 is a front, top, left perspective view of the third module with the drawers slid out of its housing; and, FIG. 32 is a perspective view of the first and the third modules from the organizer set positioned side by side.
